UNITED STATES PATENT OFFICE.

LEROY C. DOANE, OF MERIDEN, CONNECTICUT, ASSIGNOR TO THE MILLER COMPANY, OF MERIDEN, CONNECTICUT, A CORPORATION OF CONNECTICUT.

THEATER LIGHTING APPARATUS.

Application filed December 21, 1925. Serial No. 76,620.

The present invention relates to theater lighting apparatus, and is more particularly directed toward a type of apparatus suitable for supporting one or more lighting units in position to illuminate the stage, actors, scenery or other objects. The apparatus is suitable for use in foot lights, side lights or flood lights, and may also be used for display purposes, such as in lighting exteriors.

In many locations, particularly in theater lighting, it is desirable to provide a battery of lamps which throws a strong light in a desired direction, and to be able to change these lights when it is desired to vary the scene, either for the purpose of changing the intensity of illumination or the color or both. It has heretofore been necessary to provide either a number of circuits connected to different lamps, or to remove one set of lamps and replace another set, or to provide a number of batteries of lamps which will be connected into the circuit, as desired.

According to the present invention, however, the electrical connections are all permanently made inside a suitable steel box of the proper size to carry the number of lamps desired, and suitable lighting units are provided which may be attached to or disconnected from the connections in this steel box. These lighting units may include a lamp, socket, plug contacts, reflector and roundel. The box may be permanently wired up and mounted on pipes, stands or other supports when used as side or flood lights, or may be mounted in front of the stage when used as a foot light. These boxes may carry a number of contacts so arranged that the lighting units may be plugged into place, and may be carried in fixed sleeves mounted on the box.

In some cases, it is desirable to use lamps which have mogul bases, and as these large lamps with their reflectors and roundels are quite heavy, the present invention contemplates the provision of an auxiliary support for the mogul socket, lamp and reflector, so arranged that these parts (assembled as a unit) may be bodily removed, a cord and attachment plug being used to supply current to the unit.

An object of the present invention is therefore to provide a lighting apparatus wherein

one or more pairs of electrical contacts are permanently mounted in a box and wherein removable lighting units supported from the box are arranged to be connected by plugging movable contacts into fixed contacts.

As it is desirable in theater lighting to provide the lamps with reflectors suitably arranged to throw the light in the desired direction, the present invention also contemplates the use of such a reflector in lighting units and the provision of aligning devices so arranged that the units, when plugged in, will assume the proper position so as to direct the light in the desired direction.

Another object of the invention is to provide a lighting unit in which the electric lamp, reflector, and contact apparatus is permanently connected so that the unit may be plugged into the fixed contacts or removed from them expeditiously, and with a minimum likelihood of damage or breakage. These units may be provided with different sized lamps or with differently arranged reflectors, or with differently colored glass roundels, and all the units provided with a common size base so that they can be interchangeably plugged into the fixed contacts.

Another object of the invention is to provide suitable devices for holding a lamp socket and connector so that they may be properly aligned with cooperative stationary contacts and alignment devices.

Another object of the invention is to provide a locking device, which prevents the accidental removal of the lighting unit, and which holds the parts together when the lamps hang downwardly. Other and further objects will appear as the description proceeds.

The accompanying drawings show, for purposes of illustration, several of the many possible embodiments in which the present invention may take form, it being understood that the drawings are illustrative of the invention rather than limiting the same.

In these drawings:

Figure 1 is an end view of a unit of theater lighting apparatus, the reflector and roundel being shown in section;

Figure 2 is a front elevation of the unit, showing one of the lighting units;

Figure 3 is an enlarged view, with parts in

section showing a form of the apparatus which utilizes a locking collar to prevent accidental removal of the unit;

Figure 4 illustrates a slightly modified form of apparatus having no locking collar, the section being taken through the socket structure;

Figure 5 is a fragmentary view at right angles to Figure 4 showing the lighting unit removed;

Figure 6 is a fragmentary view showing a portion of the box cover and receptacle contacts;

Figure 7 is a fragmentary view at a small scale showing a number of the lighting units;

Figure 8 is a sectional view, with parts in elevation, showing an outlet box cover carrying the fixed contacts and guiding sleeve;

Figure 9 is a top plan view of such a cover;

Figure 10 illustrates an adaptation of the invention particularly arranged to use mogul sockets; and

Figure 11 is an elevational view of the same, taken at right angles to Figure 10.

The lighting apparatus contemplated by the present invention, when in the form illustrated in the drawings, utilized a sheet steel box 20 of a proper length to carry the number of lighting units desired. One or more such units may be connected to the box, and hence it may assume the form of ordinary outlet box, or in the form of a box several feet long. The box is preferably provided 30 with a removable cover 21, held in place by wing nuts 22 threaded onto studs 23, attached to the box and passing through the cover as indicated. The box is provided with a number of a knock-outs 24^a to carry the lead-in 35 wires.

One or more receptacles 24 for attachment plugs are mounted on the inside of the cover 21 by means of straps 25, which are attached to the receptacle and fastened to the cover 45 of the box by screws 26, as indicated. These receptacles have the usual T-shaped slots 24^b to receive the blades of an attachment plug. The cover is provided with holes or apertures 27 so that the receptacles are accessible from 50 the outside of the cover. It will thus be seen that it is possible to permanently wire in all the receptacles and to have all the connections to them housed in the box 20, also that the contacts in the receptacles 24 are accessible 55 through the holes in the cover of the box.

A sleeve 28 is mounted in each of the holes 27 in the cover of the box so as to project outwardly from the box. In order that the sleeve may be aligned with the contacts in the receptacle 24, it is provided with a slot 29 (see Figure 8) through which a prong 30 in the cover of the box is placed. After the sleeve is inserted in place, so as to bring the bead 32 against the cover, the inner end of the sleeve is bent outwardly as indicated at 31,

thereby permanently fastening the parts together. These sleeves 28 may be made in various forms, depending upon the type of unit with which they are to be used, as will be explained below.

As shown in Figures 1 to 4, inclusive, and in Figure 7, the lighting units which may be used in the present form of apparatus may include, as above indicated, a lamp, lamp socket, connector, reflector and roundel suitable for connecting the unit into the contacts in the receptacle 24. The reflector and roundel may be omitted where not needed. As here shown, an insulating body 33 is provided with central and shell contacts 34 and 35 for the lamp socket, and these contacts are suitably connected to a pair of blades 36 which project rearwardly from the insulating body. These blades are of the proper size and spacing to cooperate with the contacts carried in the slots 24^a and 24^b in the receptacle 24. The insulating body 33 is permanently and immovably fastened inside a metal sleeve 37 by being held between a flange 38 on the inner end of the sleeve and an internal shoulder 39. The sleeve 37 is of the proper length and diameter to surround the stem 40 of a lamp bulb 41. At the outer end 42, this sleeve is attached to a suitably shaped metal reflector 43 which reflector may, if desired, be provided with a glass roundel 44 of the selected color and shape. The sleeve 37 is also provided with a projection 45, having a predetermined angular position relative to the plug contacts 36, while the guiding sleeve 28, carried on the box cover, is provided with a slot 46 to cooperate with the projection 45. One may then slide the sleeve 37 into the sleeve 28, and the projection and slot 45 and 46 will facilitate guiding the 105 blade contacts into the contacts carried by the plug.

When the lighting apparatus is to be used in positions in which the lighting units project upwardly, there is no tendency for the lighting units to separate from the stationary box and parts carried thereby. In this case, it is not necessary to provide a locking means to prevent unintentional removal of the lighting units. A smooth sleeve may be used as indicated at 28' in Figures 4 and 5. Where the units are for use overhead or as side lights, however, it is desirable to lock them in place. Such a locking device is shown in Figures 1, 3, 7, and 8. A locking collar 47 is passed onto the sleeve 28 above the bead 32, and a bead 48 is formed near the outer end of the sleeve 28. This bead 48 will prevent the removal of the collar 47, but the collar may slide back and forth between the beads 125 48 and 32, and may be turned about as desired. This locking collar is in the form of a ring provided with a raised knurled central portion 49, and is cut away as indicated at 50 and 51 so that the projection 45 may pass 130

underneath the raised portion of the locking collar when the cut away portions 50 and 51 are in line with slot 46.

The lighting units may be provided with 5 various sized reflectors which may be arranged to direct the light in any desired direction by soldering the reflector 43 to the tube 37. Various sized and colored glass roundels may be used, and the complete unit, 10 including the lamp, may be handled as a unitary device without danger of breakage or derangement of parts. When it is desired to change the color or direction of the light emitted from the apparatus, it is only necessary to change the units by withdrawing them 15 from the guiding and alignment tubes 28, and insert other units. The parts are all arranged so that the units are interchangeable and may be plugged in with the assurance 20 that the lighting will be of the desired intensity and directed at the proper angle.

The locking collars 47, when turned out or away from the position shown in Figure 8, effectively prevent unintentional removal of 25 the units and will hold them in position when the lighting units hang down from the box. The tubular guiding and alignment sleeves not only serve for aligning the parts of the lighting units, but they make the entire construction more rigid and relieve the electric 30 contacts of mechanical load. The parts are securely held and not likely to become loose on account of repeated handling or rough usage.

35 In some cases it is desirable to provide protection for the lighting units. In this case, guard straps 52 may be suitably attached to the box, so as to extend beyond the lighting units as indicated in Figure 1, and sheet metal guards 53 and 54 may be riveted to these 40 guard frames. These parts are arranged so that the lighting units are protected against accident, without, however, interfering with the removing of the units. Where the apparatus is to be suspended from overhead 45 or is to be carried at the side, it may be conveniently mounted on pipes or other supports by providing a number of straps 55 which may be removably attached to the back side or 50 bottom of the box, as indicated in Figure 1.

In some cases it is desirable to use large units in which the lamps have mogul bases. Such an installation is shown in Figures 10 and 11, where the box 20 may be provided 55 with the guard and guard straps, as above described and also with the supporting straps 55. The cover of the box preferably carries the receptacles 24' to one side of the center. It is necessary to provide the guiding sleeve 60 used in the other form of apparatus. In this case the lighting unit includes a lamp 60, mogul socket 61, reflector 62, and mounting member 63, which is attached to the reflector and which carries the socket 61. A cord 65 64 is permanently connected with the socket

as illustrated, and is provided with an attachment plug 65 cooperable with the receptacle 24'. A convenient form of support for the lighting unit is also shown. Here the mounting member 63 is clamped inside a split 70 ring 66 and this ring is provided with threaded studs 87 which are provided with wing nuts 68 while the cover 21' is provided with a U-shaped strap 69 riveted to it, as indicated. The ends of the strap 69 are provided with 75 slots 70 for the reception of the studs 67.

It is of course understood that any number of units, such as shown in Figures 10 and 11, may be mounted on the box. These units may be readily removed by unloosening 80 the wing nuts 68 and withdrawing the studs 67 through the slots 70 and pulling out the attachment plug. With this form of device, the unit may be adjusted about the axis by turning it in the split ring 66, and 85 it may be moved into various angular positions by being turned in the stud 67 as an axis. This type of apparatus may be mounted in the same manner as any of the types above described, and it will be obvious 90 that interchangeable mogul socket lighting units may be provided for the purposes above set forth.

The form shown in Figures 8 and 9 is the same as that above described except that the 95 cover 71 is in the form of an outlet box cover having the usual attaching devices with a guiding sleeve 28 and receptacle 24 so that one lighting unit may be installed.

Theaters may be provided with a suitable 100 number of the boxes for the lighting desired, and the lighting effect may be varied by suitably placing the previously assembled lighting units. These units may be obtained in various sizes, colors and shapes so that 105 any desired effect may be obtained. These advantages may be obtained without changing the electrical connections in the boxes and ordinary stage hands may make the 110 changes.

It is obvious that the invention may be embodied in many forms and constructions within the scope of the claims, and I wish it to be understood that the particular forms shown are but a few of the many forms. 115 Various modifications and changes being possible, I do not otherwise limit myself in any way with respect thereto.

I claim:

1. A rigid self-sustaining enclosed lighting unit for display purposes and capable of being connected as a unit to stationary receptacle contacts by plugging, comprising a high wattage electric lamp, a connector having a socket for the lamp and plug contacts disposed opposite the socket, a sleeve in which the connector is fixedly mounted, the sleeve extending along the neck of the lamp to protect it, and a reflector non-rotatably carried by the sleeve and surrounding the 120 125 130

bulb of the lamp, the axis of the reflector being oblique to the axis of the lamp and at a predetermined angle to the plugging contacts.

5. 2. A rigid self-sustaining enclosed lighting unit for display purposes and capable of being connected as a unit to stationary receptacle contacts by plugging, comprising, a metallic sleeve, an insulating body fixedly 10 carried in the sleeve, said body having plug contacts projecting beyond the sleeve and a threaded high wattage lamp socket inside the sleeve, a lamp carried by the socket with its bulb projecting beyond the sleeve, a reflector fixedly attached to the end of the sleeve and surrounding the lamp bulb and having its axis oblique to the axis of the sleeve, and an alignment device carried by the sleeve and having a predetermined angular relation with the plug contacts.

3. In combination, an electric lamp, a connector having a socket for the lamp and a pair of plug contacts, a sleeve in which the connector is mounted, a reflector carried by 25 the sleeve and surrounding the bulb of the lamp, an apertured fixed support, a fixed sleeve communicating with the aperture in the support, and a pair of fixed contacts carried by the support on the opposite side of 30 the aperture, the first sleeve being slidable in the second sleeve to bring the pairs of contacts together.

4. In combination, an electric lamp, a connector having a socket for the lamp and a 35 pair of plug contacts, a sleeve in which the connector is mounted, a reflector carried by the sleeve and surrounding the bulb of the lamp, an apertured fixed support, a fixed sleeve communicating with the aperture in 40 the support, and a pair of fixed contacts carried by the support on the opposite side of the aperture, the first sleeve being slidable in the second sleeve to bring the pairs of contacts together, the two sleeves having cooperative aligning devices having predetermined angular 45 relation with the contacts.

5. In combination, an electric lamp, a connector having a socket for the lamp and a pair of plug contacts, a sleeve in which the 50 connector is mounted, a reflector carried by the sleeve and surrounding the bulb of the lamp, an apertured fixed support, a fixed sleeve communicating with the aperture in the support, and a pair of fixed contacts carried 55 by the support on the opposite side of the aperture, the first sleeve having a projection slidible in a slot in the second sleeve to guide the pairs of contacts together.

6. In combination, an electric lamp, a connector having a socket for the lamp and a 60 pair of plug contacts, a sleeve in which the connector is mounted, a reflector carried by the sleeve and surrounding the bulb of the lamp, an apertured fixed support, a fixed sleeve communicating with the aperture in 65

the support, a pair of fixed contacts carried by the support on the opposite side of the aperture, the first sleeve having a projection slidible in a slot in the second sleeve to guide the pairs of contacts together, and a locking collar non-removably carried by the second sleeve, the projection being unable to pass by the collar except when in a predetermined position.

7. In combination, a fixed support carrying a plug receptacle on one side and a guiding and supporting sleeve on the opposite side and having an aperture between the receptacle and sleeve, an insulating body having contacts cooperable with the receptacle contacts and a lamp socket, a tube in which the insulating body is fixedly mounted, the tube slidably fitting the guiding sleeve, a lamp in the lamp socket, and a reflector carried by the tube and surrounding the lamp, the lamp, insulating body, reflector and tube being in the form of a bodily removable unit.

8. In combination, a fixed support carrying a plug receptacle on one side and a guiding and supporting sleeve on the opposite side and having an aperture between the receptacle and sleeve, an insulating body having contacts cooperable with the receptacle contacts and a lamp socket, a tube in which the insulating body is fixedly mounted, the tube slidably fitting the guiding sleeve, a lamp in the lamp socket, and a reflector carried by the tube and surrounding the lamp, the lamp, insulating body, reflector and tube being in the form of a bodily removable unit.

9. In combination, a fixed support carrying a plug receptacle on one side and a guiding and supporting sleeve on the opposite side and having an aperture between the receptacle and sleeve, an insulating body having contacts cooperable with the receptacle contacts and a lamp socket, a tube in which the insulating body is fixedly mounted, the tube slidably fitting the guiding sleeve, a lamp in the lamp socket, and a reflector carried by the tube and surrounding the lamp, the tube and sleeve having cooperative aligning devices having predetermined angular relation with the contacts.

10. In combination, a fixed support carrying a plug receptacle on one side and a guiding and supporting sleeve on the opposite side and having an aperture between the receptacle and sleeve, an insulating body having contacts cooperable with the receptacle contacts and a lamp socket, a tube in which the insulating body is fixedly mounted, the tube slidably fitting the guiding sleeve, a lamp in the lamp socket, a reflector carried by the tube and surrounding the lamp, the

tube having a projection slidable in a slot in the sleeve to guide the pairs of contacts together, the lamp insulating body, reflector and tube being in the form of a bodily removable unit, and a locking collar non-removably carried by the sleeve, the projection being unable to pass by the collar except when in a predetermined position.

11. In lighting apparatus for display purposes, a plurality of interchangeable display lighting units, each comprising a lamp, a lamp base connected to plug contacts, a protective sleeve and reflector about the lamp and lamp base, the reflector being obliquely disposed relative to the axis of the sleeve, and at a predetermined angle to the plug contacts, and a box apertured to receive a plurality of the lighting units and having a plurality of pairs of receptacle contacts and guiding sleeves cooperative with the protective sleeve to permit plugging the lighting units into

the receptacles and for supporting them from the box, the contacts of the various receptacles being aligned whereby the reflectors are all directed at a predetermined angle.

25

12. In combination, a receptacle having a pair of fixed contacts, an apertured support for the receptacle, a connector having lamp socket contacts and a pair of movable plug contacts adapted to be plugged into the fixed contacts, a fixed sleeve having an alignment slot, a sleeve fixedly attached to and housing the connector, said sleeve having a projection cooperative with the alignment slot in the fixed sleeve, and a locking collar non-removably carried by the fixed sleeve, the projection being unable to pass by the collar except when it is in a predetermined position.

30

Signed at New York, in the county of New York and State of New York, this 18 day of December, 1925.
